UNITED STATES PATENT OFFICE.

ADAM D. GOETZ, OF MARTINSBURG, PENNSYLVANIA.

DIE FOR CUTTING LEATHER.

SPECIFICATION forming part of Letters Patent No. 364,643, dated June 14, 1887.

Application filed February 1, 1887. Serial No. 226,155. (No model.)

To all whom it may concern:

Be it known that I, ADAM D. GOETZ, a citizen of the United States, residing at Martinsburg, in the county of Blair, State of Pennsylvania, have invented certain new and useful Improvements in Dies for Cutting Leather, &c., of which the following is a specification, reference being had therein to the accompanying drawings.

10 This invention relates to leather-cutters, and more particularly to that class thereof in which a die is employed to cut shoe-strings, thongs, strips, &c., from scrap-leather; and the object of the invention is to provide a die 15 for the above purpose which is simple and easy of manufacture, cheap, and durable.

With these objects in view the invention consists in certain features of construction hereinafter specified, and particularly pointed 20 out in the claims.

Although herein shown and described as for the purpose of cutting leather, it is evident that the invention may be used in cutting metal, or any other material where a cut of this kind 25 is required.

Referring to the drawings, Figure 1 is a plan of a die constructed in accordance with my invention. Fig. 2 is a central vertical section on the line X-X of Fig. 1. Fig. 3 is a plan of 30 a scrap of leather after having been operated upon by a die constructed in accordance with my invention. Fig. 4 is a modification hereinafter referred to. Fig. 5 is a side elevation of a punch which may be employed in connection with the die.

Like letters of reference indicate like parts in all the figures of the drawings.

In carrying out my invention I employ a strip of metal of the desired width and length, the 40 length being determined by the length of the strip or thong it is desired to cut, said strip of metal, A, being brought to a proper temper for the purpose for which it is required. By any suitable grinding device both sides of one edge 45 of the strip are beveled, as at A', down to within a short distance of the edge. A second operation or submission of the strip to the grinding device is gone through and forms the knife-edge A². The strip is then brought to a proper 50 heat for manipulation, and is coiled around a spindle, each coil of the strip being in the same plane with the preceding coils and being

contiguous to each other—that is to say, no intermediate spacing material or device is employed. A sufficient number of the coils having been made, it will be seen, as shown in Fig. 2 of the drawings, that by reason of the bevels A' A² a space is formed between each coil, which space determines the width of the thong or strip produced by the die. By reason 55 of coiling the strip upon a spindle a space or aperture, A³, will be formed in the center of the die, which space, when the die is brought into operation upon a piece of leather or other material, will form a means whereby a suitable device may be inserted from the top of the die, forcing the strip cut out of the interstices A⁴. A suitable punch, B, provided with a cutting-nipple, B', may be inserted in the aperture A³ of the die, and by a stroke 65 of the hammer or other pressure brought to bear upon it and the die, it (the punch) will form an aperture, as B², on the blank, which will be the center of the coil cut. A knife 70 may then be employed to continue the cut of the coil to the aperture, if desired, whereby the uncut portion left by the aperture A³ will be cut.

In Fig. 4 I have shown a modification of my invention, and it consists in beveling only one 80 side of the strip of metal to form the interstices A⁴. In this modification the bevel A' is continued from about midway the strip to one of its edges, forming a cutting-edge, A².

Although I have herein shown my die 85 formed in coils, I do not limit my invention to the shape shown, as it is obvious that by providing a suitably-shaped core or spindle—for instance, triangular—the contour of the coils will partake of that shape, and thus continued 90 strips of triangular shape may be cut. The strip may simply be bent upon itself, forming a straight cut; or it may be formed in waves, thus forming different designs, which may be used for various purposes.

Having described my invention and its operation, what I claim is—

1. A die for cutting thongs, whangs, and other continuous strips, consisting of a strip of metal closely wound upon itself, tapered and ground to form a cutting-edge, each convolution being in contact with the preceding strip, substantially as specified.

2. A die for cutting thongs, whangs, and

other continuous strips of leather, consisting of a strip of metal tapered or beveled and ground to form a cutting-edge, and wound in convolute form upon a core, each convolution being in contact with the preceding one, in combination with a punch, as B, substantially as specified.

3. The strip A, beveled as at A' A², wound to form a coil and to form the space A³, whereby material cut thereby may be removed from the die, substantially as specified.

4. The combination of the strip A, beveled

as at A' A², and coiled to form the space A³, with interstices A⁴, with the punch B, having the cutting-nipple at one end, said punch being adapted to enter the space A³ of the die, substantially as and for the purpose specified. 15

In testimony whereof I affix my signature in presence of two witnesses.

ADAM D. GOETZ.
